UNITED STATES PATENT OFFICE

2,631,832

ECONOMIZER UNIT FOR CARBURETORS

Robert H. Hieger, Detroit, Mich.

Application November 12, 1949, Serial No. 126,810

6 Claims. (Cl. 261—69)

1

This invention relates to carburetors for internal combustion engines, and more particularly to an economizer mechanism or device to enable the carburetor to supply fuel to the engine in increased quantity to increase the power thereof when needed.

Most carburetors as now constructed include a device, usually referred to as an economizer or power jet, which includes a valve controlled by a piston or diaphragm subjected to the vacuum in the intake manifold to increase the rate of fuel supply to the carburetor, and thereby enrich the fuel-air mixture, when the throttle is in or near its fully open position. Such devices are often subject to leakage, which may result in drawing excess fuel into the induction passage at times when it is not wanted, thereby unduly enriching the mixture, with loss of gasoline economy. Leakage through the economizer may result from defective operation of the economizer valve, either because of wear due to vibration or because corrosion or the presence of foreign matter such as grit prevents it from seating properly.

Defective operation of the economizer may also result from a defective or maladjusted valve spring. Thus, if the economizer valve is designed to open at a suction in the manifold of, say, seven inches of mercury, it may open at a lower or a higher suction, causing either a waste of fuel or faulty operation of the engine.

Defective operation of the economizer may also result from leakage of the fuel through the economizer, which may result in draining the float chamber by gravity while the car is standing with the engine not in operation.

Defective operation of the economizer may result from various other causes, and is difficult to detect, since commercial carburetors are so constructed that it is impossible, without disassembling the carburetor, to apply a measured amount of suction to the fuel outlet thereof and to the vacuum connection, and measure the resulting fuel flow. Also if leakage is found or suspected, it is difficult to remedy by means of ordinary shop tools.

An object of the present invention is to provide a carburetor comprising an economizer mechanism having improved means for preventing leakage of fuel therethrough.

A further object of the invention is to provide an economizer wherein the valve is readily replaceable and which will not often get out of proper working order.

A further object of the invention is to provide a carburetor wherein the economizer unit may

2

readily be withdrawn for testing, cleaning and adjustment, and replaced without altering its adjustment.

A further object of the invention is to provide an economizer mechanism which is usable in known types of carburetors in substitution for the corresponding mechanism originally supplied with the carburetor.

The invention comprises an economizer of the diaphragm type including a shell or body which, with its contained elements, may be removed as a unit, tested by applying suction thereto, adjusted by means of suitable tools, and replaced in the carburetor without disassembling the unit or disturbing the adjustment. Leakage between relatively moving parts of the unit is prevented by sealing members of the type disclosed in my co-pending application Serial No. 83,688, filed March 26, 1949, such members providing a yielding and relatively frictionless yet fluid-tight seal between the parts.

Further objects and advantages of the invention will be apparent from the following description, taken in connection with the appended drawings, in which:

Fig. 1 is a diagrammatic view of a carburetor and the fuel system thereof showing, on an enlarged scale, the device of the present invention incorporated therein, with the economizer valve in closed position.

Fig. 2 is an enlarged sectional view of the economizer unit and its associated parts, showing the economizer valve in open position.

Fig. 3 is a perspective view showing the economizer valve embodying the present invention, separately.

It is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The carburetor shown in the drawing is of the downdraft type commonly used with automobile engines, but may be of any known or suitable construction. It comprises a body 8 forming an induction passage which includes an air inlet 10, a main venturi 12, and a mixture outlet 14 designed to be connected to the intake manifold of an internal combustion engine, not shown. The induction passage is controlled in the usual manner by a manually operated throttle valve 16.

Usually an air cleaner, such as is indicated fragmentarily at 18, is connected to the air inlet.

Fuel is supplied to the induction passage from a reservoir 20, which in the example shown is a float chamber having a float 22 therein, which actuates a fuel valve 24 controlling a fuel inlet 26 leading from any suitable source of supply. Thence the fuel flows through passages 28, 30 to the main fuel nozzle 32, which discharges at the throat of the main venturi 12. In the example shown, a second venturi 34 is provided to form a discharge member for the main nozzle. A metering orifice 36 is provided in the passage 28, as is the usual practice, and an idling fuel passage 33 of any suitable construction may lead from the passage 30 to a point above the fuel level L and discharge adjacent the edge of the throttle 16 when the same is in closed position. Suitable acceleration pump mechanism, as well as check valves, vents, and metering orifices may be provided, as known in the art.

The economizer constituting the present invention comprises a body or shell having a threaded portion 46 which is screwed into a threaded bore in the bottom 48 of the float chamber so that the entire unit may readily be removed from the carburetor. The bottom 48 cooperates with a cover plate 50, secured thereto by bolts 51, to form a vacuum chamber 52 which is connected by a vacuum passage 54 to the induction passage of the carburetor at a point posterior to the throttle 16.

The lower portion of the economizer body is flared to form a recessed base 56 the lower edge 58 of which is spun inwardly to retain a cupped disk 60 having a central aperture 62. A flexible diaphragm 64 has its edges clamped between members 56 and 60 and is subjected on its underside to the vacuum in the induction passage posterior to the throttle. The space above the diaphragm 64 forms a chamber 65. The diaphragm 64 is preferably formed of neoprene, an elastomer which is highly resistant to gasoline and to the acids and other impurities contained therein.

The diaphragm is connected by any suitable coupling 66 to a plunger 68 which is reciprocable within a septum 70 formed in base 56 of the economizer body. The upper reduced end of the plunger constitutes a stem 72 which is designed to actuate a retaining member 74 forming part of the movable member of the economizer valve, to raise it off its seat when the manifold vacuum is low, as shown in Fig. 2, and to close it when the manifold vacuum is high, as shown in Fig. 1.

A recessed collar 76 is adjustably fixed to an intermediate portion of plunger 68, as by a driven fit, and forms a seat for a compression spring 78 which urges the plunger upwardly, the lower end of the spring being seated against septum 70. The bottom wall 48 of the float chamber is formed with an annular recess 80 which communicates with radial ports 81 formed in the portion 46 of the economizer, and thence with an outlet passage 82 which is connected to passage 30 by a metering orifice 83.

A tubular member 84 forms the upper portion of the economizer body, and has an externally threaded sleeve 85 which is threaded into the upper end of the portion 46, leakage between the two being prevented by a gasket 86. A bored plug 88 is threaded into the upper end of the member 84, and a retaining plug 90 is driven into the bore of plug 88, to serve as an adjustable seat for a light compression spring 90 which bears against

the retaining member 74 to urge the same toward its seat 92.

Radial ports 94 connect the float chamber 20 to the interior of the economizer body, whence fuel flows through a port 96 to the fuel space 95 within member 84, past the collar 76, and thence through ports 81, passage 82, and orifice 83 to the main nozzle 32. Plug 89 is provided with a relief port 98 which connects with the interior of the float chamber, to permit the member 74 to move freely.

The retaining member 74 is of circular form, and has a projection 99 at its top to provide a seat for the spring 90. An axial bore in member 74 receives the stem 72 in loose fitting relation to form a one-way rockable connection therewith. The member 74 has a depending flange 100 which embraces the stem 72 and is spun outwardly to retain an annular washer 102, which acts to contact the shoulder of the seat 92 and to be deformed thereby when the valve is closed. The washer 102 thus forms with the retaining member 74 a valve element which, when manifold vacuum causes stem 72 to move downwardly, is moved by spring 90 into contact with the valve seat 92 surrounding the port 96, to thereby obstruct the flow of fuel as indicated in Fig. 1. At lower vacuum, the member 74 is moved by spring 78 to the position indicated in Fig. 2, to permit an auxiliary flow of fuel through port 96 and thence to the carburetor.

Sufficient clearance is provided between plunger 68 and septum 70 to permit free movement of the plunger. In order to prevent leakage of fuel downwardly from the space 95 to the chamber 65 above the diaphragm 64 during the time when the economizer valve is open, such as when the engine is operating with a nearly open throttle or when the engine is still, an annular sealing member or O-ring 103 is fitted about a collar 104 on the plunger, in such relation that when the plunger is in its uppermost position, the sealing member is deformed slightly as indicated in Fig. 2 and acts to prevent flow of fuel from the space 95 to the chamber 65. The member 103, as well as the washer 102, is of the type disclosed in applicant's copending application Serial No. 83,688, filed March 26, 1949, being of circular cross section and made of material which is capable of elastic distortion under the pressures to which it is subjected, and impervious and resistant to gasoline and to the acids and other impurities contained in commercial gasoline. An example of a material which is satisfactory is Buna N, which has also a low coefficient of friction to metal in the presence of gasoline.

The economizer may be withdrawn from the carburetor, inspected, adjusted so that the fuel valve will open at the desired degree of vacuum, and replaced as a unit in the carburetor without disturbing the adjustment. In order to increase the initial stress of spring 90, and thereby decrease the degree of vacuum required to seat the retaining member 74, the plug 98 may be driven downwardly without disassembling the economizer unit. In order to decrease the initial stress of spring 90, the plug 88 may be unscrewed and the plug 98 driven in the opposite direction.

Although the invention has been described with reference to two specific embodiments thereof, it may be embodied in other forms within the skill of artisans in this art, and is not limited except in accordance with the terms 70 of the following claims.

I claim:

1. In an economizer device for an internal combustion engine carburetor, a casing, a fuel passage and a vacuum chamber in said casing, a partition having an opening and provided in said casing to separate said fuel passage from said vacuum chamber, an economizer valve controlling said fuel passage and including a movable member, a vacuum controlled plunger connected to said movable member and movable through the opening in said partition, and a washer formed of elastomer and embracing said plunger adjacent said opening in said partition to prevent leakage therethrough when the economizer valve is fully open.

2. The invention defined in claim 1 with said washer serving also to limit the movement of the plunger in the opening direction of the economizer valve.

3. The invention defined in claim 1, with said movable member including an elastomer controlled by said plunger and movable thereby into its open position, and a spring moving said elastomer to a seated position constituting the closed position of the economizer valve.

4. An economizer device for a carburetor having a fuel reservoir and a fuel conduit leading therefrom provided with a calibrated orifice, said device comprising a body designed to seat in an aperture in the reservoir and to project into the interior thereof, said body being provided with a fuel passage by-passing said orifice, a valve seat formed on said body in the reservoir projecting end thereof to control said passage, an economizer valve unit adapted to cooperate with said seat to open and to close said fuel passage, a chamber having a movable wall responsive to varying pressure in the chamber, a sealing valve seat provided between said passage and said

chamber to separate the latter from said passage, a plunger connected to said movable wall to be moved thereby, said plunger being adapted to move said economizer valve unit to open said passage and spring means adapted to hold the economizer valve unit against said valve seat when the plunger is retracted, and a sealing valve unit including an annular member made of rubber-like material and adapted to be pressed against the seat provided between said passage and said chamber to seal the same when said economizer valve unit is fully open.

5. The invention defined in claim 4, the economizer valve unit including a sealing member made of a rubber-like material resistant to fuel and impurities thereof.

6. The invention defined in claim 4, said economizer valve unit including a metal member loosely slidable on the end of the plunger for a predetermined distance, said member carrying a sealing element made of a rubber-like material resistant to fuel and impurities thereof.
